UNITED STATES PATENT OFFICE

HERBERT R. POLLEYS, OF NEW HAVEN, CONNECTICUT, ASSIGNOR TO NATIONAL INDIA RUBBER COMPANY, OF BRISTOL, RHODE ISLAND, A CORPORATION OF RHODE ISLAND

CEMENTING MACHINE

Application filed July 24, 1929. Serial No. 380,528.

This invention relates to a machine for applying cement to the toe portion of articles of footwear.

In the art of manufacturing rubber fabric footwear, it is customary to apply a cap of rubber over the toe of the fabric upper. The cap of rubber is cemented to the fabric. It has been customary heretofore to apply the cement manually to the fabric over the area to be covered by the rubber cap and thereafter to press the rubber cap thereon so as to adhesively unite the rubber cap to the fabric. The operation of applying cement manually has not been satisfactory inasmuch as it requires considerable manual labor, is liable to defects arising from human error, such as an inadequate quantity of cement or the improper distribution of the cement over the fabric or spreading the cement beyond the area to be covered by the cap of rubber thereby rendering the article of footwear unsightly. To reduce the cost and increase the rapidity and render this operation of applying cement to the toe of the shoe more satisfactory is an object of this invention.

It is the object of this invention to provide a machine which will perform the function of applying cement to the toe of a fabric upper. It is also an object of this invention to provide a toe cementing machine in which a bead of cement is applied across the toe which delineates and sharply marks off the area over which the cement is distributed. It is also an object of this invention to provide a machine which will thoroughly distribute cement over the area so delineated. Other objects and advantages of the present invention will appear from the following detailed description taken in connection with the accompanying drawings, in which:

Fig. 1 is a side elevation of the essential parts of the machine with parts broken away.

Fig. 2 is a detail view showing the brush and cup partly in section.

Fig. 3 is a front elevation of the brush and cup.

Fig. 4 is a plan view of the driving mechanism.

Figs. 5 and 6 are side elevations of parts of the mechanism shown in Fig. 4.

According to my invention an article of fabric footwear 1 which has been lasted and to which the toe cap is to be applied is brought into contact at its toe portion with the rim of a cup 2. An adjustable support 3' suitably mounted upon the frame of the machine is provided for properly supporting the article of footwear 1 relative to the cement applying parts of the machine. The edge of the cup 2 serves to apply a line or bead of cement across the toe of the shoe. This line or bead of cement provides a relatively thick deposit of cement along that line so as to securely unite the fabric and the margin of the toe cap later to be applied to the shoe. The line or bead of cement also serves to mark off and delineate the area over which the cement is distributed.

The cup 2 is mounted for rotation in a casing 3. Shoulders on the cup and casing respectively as indicated at 4 serve to provide one bearing face between the cup and casing and the shoulders as indicated at 5 between the cup and back plate 6 secured to the casing serving to form the other bearing surface between the cup and the casing. The cup 2 is provided with a ring gear 7 with which meshes the pinion 8 for driving the cup in rotation. The pinion 8 is fixed upon shaft 9 upon which is slidably keyed the clutch member 10 which cooperates with clutch member 11 rigidly fixed to a shaft 12 driven in rotation from any suitable source of power, such as the motor 13 and reduction gear 14.

As the cup 2 rotates cement is applied to the rim thereof in the form of a bead through the orifice 15 of the box 16 provided with plates mounted in juxtaposition to the disk 2. Cement is provided from any suitable source of supply as the cement tank 17 connected with the box 16 through the pipe connection 18. A scraper plate 19 removes the excess cement from the edge of the cup 2, which excess cement is carried off through a suitable spout 20.

In order satisfactorily to unite a rubber toe cap with the toe of the fabric upper, it is necessary that cement be distributed over the entire area to which the toe cap is united. In

order to effect such distribution of cement, a brush 21 is positioned within the cup 2 in a manner such that it may be moved over the toe of the shoe to spread cement thereover. 5 The cement may be supplied to the brush directly through any suitable pipe connection, not shown, or the overflow of cement from the edge of the disk 2 may be sufficient for distribution over the toe of the shoe, or the cement present on the parts of the shoe adjacent the toe due to previous cementing operations may be availed of for distribution over the toe. The brush 21 is mounted on arm 22 which is rigidly fixed to the shaft 23 which 10 rigidly carries pinion 24, the shaft 23 being mounted for rotation in the casing 3, and the cup 2 being open from the back so as to permit the arrangement of the brush 21 therein as shown in the drawings. The arm 22 and brush 21 are driven in oscillation by racks 25 which mesh with the pinion 24 and which are movable in and guided by ways 26. The racks 25 are oscillated by the cams 27, the riders 28 being provided on the extremities of the 15 racks for contact with the faces of the cams 27. The cams 27 are of such shape and so mounted upon their shaft that upon rotation thereof the racks 25 are moved in opposite directions, thereby effecting the oscillation of the brush 21. The upward movement of one of the racks 25 forces the other rack downwardly so as to maintain its rider in contact with the corresponding cam 27.

In order that the article of footwear 1 may 35 be held in proper position while the bead or line of cement is applied by the edge of the cup 2, it is of advantage to stop the rotation of the cup at that time. Therefore the cup 2 rotates when the machine is not in use and 40 is stationary when it is in use. When the toe of the article of footwear 1 is inserted within the cup 2, and before the rotation of the cup 2 has been stopped and the article of footwear brought into contact with the rim thereof, it is of advantage to have the brush 21 stationary so that the article of footwear may be 45 more easily and accurately positioned. When the cement is actually applied, the article of footwear is brought into contact with the edge of the cup 2 which transfers its bead to the shoe and the brush 21 is moved in oscillation across the toe of the shoe so as to distribute cement thereover. Therefore 50 mechanism is provided for simultaneously stopping the rotation of the cup 2 and for setting the brush 21 into oscillation. The description of such mechanism follows:

The clutch member 10 is provided with a 55 groove in which rides the pin 28^a upon one extremity of one arm of bell-crank 29 mounted for rotation on the frame of the machine. The other arm of the bell crank 29 is connected with rod 30 leading to a foot treadle, not shown. Upon the operation of the treadle, bell crank lever 29 is turned to open

the clutch 10—11 thereby stopping the rotation of the cup 2.

The bell crank 29 carries a dog 31 rotatably mounted thereon and spring urged in a direction so as to engage with a ratchet 32. The ratchet 32 is fixed upon shaft 33, which shaft rigidly carries a notched wheel 34. The wheel 34 cooperates with the latch 35 fixed upon shaft 36 suitably mounted for rotation on the frame of the machine. Shaft 36 carries rigidly a lever 37, one end 38 of which is provided with a cam edge which cooperates with pin 39 carried by clutch member 40. The clutch member 40 is urged in a direction to effect engagement of the clutch by the spring 41. When the cam face 38 is in engagement with the pin 39, the clutch is held disengaged. Motion of the foot treadle before referred to operates the bell crank 29 thereby rotating the notched wheel 34 which through the latch 35 rotates the lever 37 so as to release the clutch 40 thereby setting the shaft 41 upon which cams 27 are mounted into rotation, the shaft 41 then being connected to shaft 42 driven from a suitable source of power such 50 in this instance as the motor 13, reduction gear 14 and transmission system 15'. Rotation of the cams 27 effects the oscillation of the brush 21, as before described, slightly after the stopping of the rotation of the cup 2.

It has been found most satisfactory in the operation of the machine to drive the brush 21 across the toe of the shoe a limited number of times thereby adequately distributing the cement over the toe of the shoe and at the same time materially shortening the operation. In addition it is of advantage to have the brush stop oscillating while the cup 2 is still stationary so that the article of footwear may be removed from the machine without the motion of the brush 21 interfering. In order to effect this operation of the brush 21, the clutch 40 is of the limited number of revolutions type and operates as follows:

Shaft 41 has a spur gear 43 fixed thereon, which meshes with the idler pinion 44 loosely mounted for rotation upon the shaft 36 which in turn meshes with gear 45 fixed upon shaft 46 which rigidly carries cam 47. When the lever 37 is lifted by pressing on the treadle of the machine, the chain of gears 43, 45 and cam 47 are set into rotation. The lever 37 is provided with a cam follower 48 which rides upon cam 47 and the shape of the cam 47 is such that in its rotation it maintains the lever 37 in a raised position for a certain number of revolutions of the shaft 41 depending upon the ratio of the gears 43—45. The spring and lever system 49 is provided for urging the cam follower 48 into contact with the cam 47. When the cam 47 has completed its rotation, the lever 37 is rotated by the spring lever system 49 so as to bring the cam face 38 into contact with the pin 39 to effect the separation of

the clutch 40 and to stop the oscillation of the brush 21. As the shaft 36 carrying the cam lever 37 is rotated in its original position, the latch 35 is then moved into operative relation with the tooth wheel 34. A catch 50 is carried by lever 51, the catch being urged into operative relation with the tooth wheel by the spring 52, the catch 50 being for the purpose of preventing backward rotation on the wheel 34 when the foot treadle is released, thereby insuring a complete forward movement of wheel 34 when foot treadle is operated downwardly.

The article of footwear is then removed from the machine and the cup 2 set in rotation by releasing the treadle. The cycle of operations may then be repeated.

While this invention has been described as being useful in applying cement to the toe of an article of footwear, it is obvious that it may be used to apply cement to other articles to which cement might be similarly applied.

While one specific form of the invention has been disclosed by way of illustration, it is not intended thereby to limit the invention thereto inasmuch as variations may be made in the machine without departing from the scope of the invention indicated by the following claims.

Having thus described my invention, what I claim and desire to protect by Letters Patent is:

1. A toe cementing machine having in combination, means for distributing cement across a toe, and means for limiting the area over which the cement is distributed.

2. A toe cementing machine having in combination, means for distributing cement across a toe, and means for applying a bead of cement to form the boundary of the area over which the cement is distributed.

3. A toe cementing machine having in combination, a rotatable member having a rim adapted to apply a bead of cement across a toe, and means for distributing cement over the toe within the area delineated by the bead of cement.

4. A toe cementing machine having in combination, a rotatable member having a rim adapted when stationary to apply a bead of cement across a toe, and means movable while the member is stationary for distributing cement over the toe within the area delineated by the bead of cement.

5. A toe cementing machine having a rotatable member provided with a rim adapted when stationary to apply a bead of cement across a toe brought into contact therewith, and means for supplying cement to the member while it rotates.

6. A toe cementing machine having a rotatable member provided with a rim adapted when stationary to apply a bead of cement across a toe brought into contact therewith, means for supplying cement to the member

while it rotates, means for driving the member in rotation, and means for stopping the member at the will of the operator.

7. A toe cementing machine having means mounted for oscillation across a toe cap and adapted to distribute cement thereover, and means for driving the first mentioned means in oscillation at the will of the operator.

8. A toe cementing machine having a rotatable member provided with a rim adapted when stationary to apply a bead of cement to a toe brought in contact therewith, and means oscillatable when the member is stationary for distributing cement over the toe within the area delineated by the bead of cement.

9. A toe cementing machine having a rotatable member provided with a rim adapted when stationary to apply a bead of cement to a toe brought in contact therewith, means oscillatable when the member is stationary for distributing cement over the toe within the area delineated by the bead of cement, and means for supplying cement to the rotatable member when it rotates.

10. A toe cementing machine having a rotatable member provided with a rim adapted when stationary to apply a bead of cement to the toe brought in contact therewith, means oscillatable when the member is stationary for distributing cement over the toe within the area delineated by the bead of cement, means for supplying cement to the rotatable member when it rotates, and means for stopping the rotation of the member and setting the first mentioned means into oscillation.

11. A toe cementing machine having in combination, a rotatable cup having a rim adapted to supply a bead of cement across a toe brought in contact therewith, and a brush mounted for oscillation within the cup for distributing cement over the area of the toe limited by the rim of the cup.

12. A toe cementing machine having in combination, a rotatable cup having a rim adapted to supply a bead of cement across a toe brought in contact therewith, a brush mounted for oscillation within the cup for distributing cement over the area of the toe limited by the rim of the cup, and means for stopping the rotation of the cup and setting the brush into oscillation.

13. A toe cementing machine having in combination, a rotatable cup having a rim adapted to supply a bead of cement across a toe brought in contact therewith, a brush mounted for oscillation within the cup for distributing cement over the area of the toe limited by the rim of the cup, means for stopping the rotation of the cup and setting the brush into oscillation, and means for supplying cement to the rim of the cup.

14. A toe cementing machine having in combination a rotatable cup having a rim adapted to supply a bead of cement across

- a toe brought in contact therewith, a brush mounted for oscillation within the cup for distributing cement over the area of the toe limited by the rim of the cup, means for stopping the rotation of the cup and setting the brush into oscillation, and means for automatically stopping the oscillation of the brush while the cup is stationary.
15. A toe cementing machine having means mounted for oscillation across a toe cap and adapted to distribute cement thereover, means for driving the first mentioned means in oscillation a predetermined number of times at the will of the operator, and means for automatically stopping the oscillation of the first mentioned means.
16. A toe cementing machine having a rotatable member provided with a rim adapted when stationary to apply a bead of cement to a toe brought in contact therewith, means oscillatable when the member is stationary for distributing cement over the toe within the area delineated by the bead of cement, and means for automatically stopping the motion of the oscillatable means after a predetermined number of oscillations when the member is stationary.

Signed at New Haven, county of New Haven, State of Connecticut, this 19 day of

July, 1929.

HERBERT R. POLLEYS.
